J. SMITHLINE

STETHOSCOPE

Filed Aug. 25, 1923

INVENTOR
Jacques Smithline
BY *Morris Kirschner*
ATTORNEY

UNITED STATES PATENT OFFICE.

JACQUES SMITHLINE, OF BROOKLYN, NEW YORK.

STETHOSCOPE.

Application filed August 25, 1923. Serial No. 659,246.

To all whom it may concern:

Be it known that JACQUES SMITHLINE, citizen of the United States, residing at New York, borough of Brooklyn, in the county of Kings and State of New York, has invented certain new and useful Improvements in Stethoscopes, of which the following is a specification.

This invention relates to stethoscopes.

10 One object thereof is to provide a device of the character described which shall be capable of use for giving sounds with or without amplification as may be desired and which may be easily applied to any 15 desired portion of the body in such manner as to give full and satisfactory sounds.

Another object is to provide in a stethoscope a practical and efficient attachment whereby the sounds may be transmitted 20 without amplification.

Another object is to provide an instrument of the character described which shall be simple in construction, comparatively cheap to manufacture and efficient in operation to a high degree.

Other objects of this invention will in part be obvious and in part hereinafter pointed.

The invention accordingly consists in the 30 features of construction, combinations of elements and arrangement of parts which will be exemplified in the construction hereinafter described and of which the scope of application will be indicated in the following claims.

In the accompanying drawing in which is shown one of the various possible illustrative embodiments of this invention,

40 Figure 1 is a longitudinal cross-sectional view of the stethoscope showing same in use for giving sounds without amplification.

Figure 2 is a view showing the parts disassembled of the attachment.

45 Figure 3 is a cross-sectional view taken along line 3—3 of Figure 1.

Referring in detail to the drawing the instrument embodying my invention there shown is seen to comprise a head 10 having 50 the interior surface thereof dished as at 11 so as to provide a conical space or air chamber 12. Extending from the rear of the head is a tubular Y-connector portion 13 to

55 which are attached the flexible tubes 14, 14', having at their ends the ear pieces 15. The legs 13^a, 13^b of the Y-connector 13 commu-

nicate with the central opening 16 extending into the chamber 12. At the point of communication the material of the head member 10 is cut away so as to provide a cylindrical recess 17 concentric with the opening 16. A diaphragm 18 of suitable material such as hard rubber is disposed in front of the air chamber 12 in operative relation to the annular space 17 and the conical space 12. This diaphragm is secured along its outer edge to the head member 10 in any suitable manner. In the form shown in the drawing, the head member is provided with a rear annular shoulder 19 and a sleeve member 20 having a bezel 21 which is fitted over the head member so as to rest against this shoulder 19 with the bezel 21 pressed against the outer edge of the diaphragm 18. Extending from the head member and through sleeve member 20 are pin projections 22, 22' for the purpose hereinafter described.

The device as thus far described may be employed in the ordinary manner for exploring the rear and front chest walls so as to get the lung sounds, where amplification is usually desirable. The sounds are caused to impinge directly on the outer surface of diaphragm 18 and thereby create sound waves within the air chamber 12 and then concentrated into the annular space 17. They are then further concentrated into air waves of smaller uniform diameter into the passage 16 and thence pass through the legs 13^a, 13^b and the tubes 14, 14' to the ear. I have found that for ordinary uses of the stethoscope such as just described this device is exceedingly sensitive and gives very satisfactory and efficient operation, a dominating feature of the device being the construction of the head member so as to provide the conical air chamber 12 which gradually tapers, so to speak, the air waves into an auxiliary or secondary cylindrical chamber 17 whence the waves are further concentrated into a third cylindrical chamber of smaller diameter, in this way concentrating the sound and propagating it with practically no loss of intensity to the ear.

In examining the heart it is often not desirable to have any amplification, and yet the instrument should be such as to give proper and audible sounds so as to reflect the true condition of the heart. Furthermore, in exploring the heart it is sometimes not possible

with a head member such as 10 to get good contact with the body by reason of peculiar formations of the body, as for example, where a person has a very lean chest wall 5 so that the ribs are quite exposed thus affording an insufficient smooth contact surface for a normal size stethoscope. Also such head can not be used with advantage in exploring the neck portion so as to give sounds 10 from the neck vessels. It will be understood, of course, that where improper contact is had between the head of the stethoscope and the portion of the body explored, a large portion of the sound is lost and not conveyed 15 through the stethoscope. To meet these conditions I have, therefore, provided an attachment comprising a neck 23 terminating at its free end in a bell shaped mouth 24 adapted to be placed against the body and 20 having at its other end a diaphragm 25 shown in detail at (a) of Figure 2, and which may be threaded on the neck as shown in Figure 1 or integral therewith. This diaphragm has a body portion 25 of substantial 25 thickness and is of tapering cross-section as at 26^a so that adjacent its periphery 27 it is comparatively very thin. The neck member 23 and diaphragm 25 are made of suitable material such as hard rubber and the latter is fitted into a sleeve 28 similar to sleeve 21 but of larger diameter so as to snugly fit over the latter. This sleeve 28 is likewise provided with a bezel 28^a which rests against the edge of the diaphragm 25 30 when the sleeve member is fitted tightly over the head portion 10. Slots 30 shaped so as to provide recesses 30^a for the pins 22, 22' on the head member are cut in the walls of the sleeve 28 so that when the latter is fitted 35 over the head member the pins register in said recesses and are held tightly against the walls of the slots, then the member 28 is rotated until the pins have moved away from the recesses 30^a into the slots. 40

45 The sound waves enter the mouth 24 and are concentrated into the opening or passage 23^a in the neck piece 23, which is quite small in comparison to the diameter of the mouth 24. The waves thus concentrated into the 50 cylindrical chamber 23^a impinge on diaphragms 18 and 25. By reason of the thick body and thin peripheral portion of diaphragm 27, a small portion of the sound energy is expended in vibrating diaphragm 25, the remainder being transmitted through the head member 10 and is in consequence 55 not concentrated but nevertheless has sufficient strength to give audible sounds and truly reflect the condition of the portion of the body being explored.

It will thus be seen that there is provided a device in which the several objects of this

invention are achieved and which is well adapted to meet the conditions of practical use.

65

As various possible embodiments might be made of the above invention and as various changes might be made in the embodiment above set forth, it is to be understood that all matter herein set forth or shown in the accompanying drawings is to be interpreted as illustrative and not in a limiting sense.

Claims:

Having thus described my invention I desire to obtain by Letters Patent,

75

1. In a stethoscope, in combination with a drum head having a diaphragm fastened thereon, means secured to said head for muffling the sounds transmitted by the diaphragm, said means being removable independently of said diaphragm fastening and including another diaphragm disposed in non-contactual relation opposite said first mentioned diaphragm and having greater inertia than the latter.

85

2. In a stethoscope, in combination with a drum head having a diaphragm fastened thereon, means secured to said head for muffling the sounds transmitted by said diaphragm, said means being removable independently of said diaphragm fastening and comprising an auxiliary sound transmitting device including a diaphragm disposed in non-contactual operative relation to said first mentioned diaphragm and a sound receiving member having an enlarged mouth portion adapted to receive the air waves, and a neck portion having a narrow passage in communication with said mouth portion and adapted to transmit the air waves to said last mentioned diaphragm, said mouth portion being of substantially smaller diameter than the head portion.

90

3. In a stethoscope, in combination with a drum head having a diaphragm fastened thereon, means secured to said head for muffling the sounds transmitted by said diaphragm, said means being removable independently of said diaphragm fastening and comprising an auxiliary sound transmitting device including a diaphragm disposed in non-contactual operative relation to said first mentioned diaphragm and having a comparatively thick body portion and a thinner peripheral portion and a sound receiving member having an enlarged mouth portion adapted to receive the air waves, and a neck portion having a narrow passage in communication with said mouth portion and adapted to transmit the air waves to said last mentioned diaphragm.

100

In testimony whereof I affix my signature.

JACQUES SMITHLINE.
